CRACKING PROCESS

Felix J. Skowronski, Colonia, N. J., assignor of
one-half to, The Winkler-Koch Patent Com-
pany, Wichita, Kans., a corporation of Kansas

Application April 5, 1940, Serial No. 328,118

1 Claim. (Cl. 196—52)

The present invention relates to an improvement in the cracking or conversion of hydrocarbons, specifically for the purpose of producing lower boiling hydrocarbons from higher boiling hydrocarbons.

One of the primary objects of the invention is the employment of a colloidal catalyst; that is to say, a material of catalytic activity which is colloidally dispersed in the oil prior to the cracking operation, the solution or dispersion of which is introduced into the oil during the cracking operation.

Another object of the invention is a cracking system employing colloidal catalytic cracking as its first step, followed by separation of the resulting cracked products into residuum, vapors of the desired end boiling point, gases, and an intermediate fraction which may be employed as a recycle stock, which latter is cracked separately and noncatalytically, the vapors and other products thus produced being commingled and directed into the same vapor-separating, residuum-disposing, and condensing system.

A still further object of the invention is to disperse colloidally a suitable catalytic material, for example aluminum oxide, in the cracking stock—for example, a gas oil—and to inject the resulting dispersion into a soaking section of a tubular cracking system so as to avoid the preliminary heating of the mixture during the early heating stages, some of the oil being heated to the desired cracking temperature, gradually having the colloidal dispersion injected into the oil at one or more points of a soaking coil after it has attained the desired cracking temperature or after it has been maintained at said temperature for the necessary time to effect the desired amount of cracking.

In its preferred embodiment, the colloidal cracking portion of the invention is effected as a single pass operation while thermal cracking may be of the recycling type.

For a better understanding of the invention, there is filed herewith a single drawing which illustrates the fundamental principles of the invention. This drawing however is to be considered as entirely diagrammatic and is in nowise to be taken as a limitation upon the invention as herein disclosed and claimed.

It has already been proposed in the past, in certain batch operations, to employ colloidal materials such as colloidally dispersed nickel and the material known as colloidal carbon, which however is not truly a colloidally dispersible substance. The present invention is to be distin-

guised therefrom in that it employs a really colloidally dispersed catalyst, specifically aluminum oxide, although the use of other colloidally dispersible catalytically active materials is to be considered as within the scope and purview of the invention. Such materials may be metallic or inorganic elements or compounds, such as silicon dioxide, magnesium oxide, and metallo-organic compounds capable of decomposing under cracking conditions so as to yield a sufficiently dispersed catalytic material.

The particular advantage residing in the employment of a colloidal catalyst lies in the fact that it presents, for any given weight thereof, the maximum available surface. Calculations will easily prove that a given quantity of a colloidally dispersed material presents a much greater surface area than a noncolloidal product. Take for example aluminum oxide, which has a specific gravity of 2.2, and reduce it to a very fine powder. Assuming that the resulting particles are spherical and $\frac{1}{40}$ micron in diameter, it will be found, by making the necessary calculations, that a single particle of this material will weigh 0.0000000737 gram and that there are 13,564,000 particles in one gram. Therefore one gram of this material will have an available area of $68,182$ square millimeters $= 6.8182 \times 10^4$. Taking the same material but reducing it to colloidal particles the largest of which can be assumed to be no more than 200 millimicrons in diameter and assuming that the specific gravity is the same, it can soon be ascertained, by making the necessary calculations, that the surface in square millimeters for one gram of this material is equal to 1.364×10^7 . The surface ratio of one gram of colloidal catalyst to one gram of a noncolloidal catalyst will show that the colloidal catalyst has over two hundred times the surface for any given weight. Furthermore, from a consideration of the kinetic theory, one may expect an additional advantage of the colloidal catalyst over the noncolloidal catalyst from an increase in the equivalent catalytic surface area as a result of the Brownian movement to which such colloidal particles are subject.

A method of producing an efficient colloidal catalyst may comprise the following: Alumina may be very finely ground and then put—together with an oil, for example a gas oil—through a suitably constructed colloid mill in order to produce what is usually termed a colloidal solution of alumina in the oil. Appropriate amounts of this solution may then be injected into the main

ody of oil which is to be cracked. The amount of catalyst may vary considerably and may range up to about 200% of the weight of the oil, but a little as from about 1% to 2% by weight of colloidal dispersed alumina on the weight of the oil to be cracked will still be effective.

Perhaps the best way of producing, for instance, colloidal alumina is to employ the Svedberg modification of the Bredig method. In Svedberg's apparatus the distribution is carried out electrically, for instance by sparking electrodes, containing a conducting material and aluminum oxide, under the surface of the oil in which the material is to be dispersed. For example, it has been found that a satisfactory catalyst for carrying out the present invention may be produced by forming electrodes consisting of finely powdered aluminum oxide, Al_2O_3 , and a conducting substance, the electrodes being in the form of sticks. Two of these electrodes are immersed in an oil under conditions preventing combustion, whereupon an electric arc is produced by any of the well-known means, thus setting up an arc between the electrodes. It is, of course, obvious that the oil must be adequately cooled to prevent its volatilization. As a result of the local heat produced as well as the electrical effects, the colloidal dispersion of the catalyst, for instance the alumina, in the oil will form. The spark or arc may be produced by an induction coil, by means of a low frequency transformer, by suitable high potential direct current such as from 500 volts and upward, or by means of a low frequency transformer which produces an air spark gap which is then immersed upon a secondary circuit by means of a transformer so as to produce a high frequency arc between the electrodes immersed in the oil. It has been found that in general the last mentioned method is the most efficacious. However, the invention is not to be limited by the particular means for colloidally dispersing a cracking catalyst in oil, for such methods are well within the skill of the trained chemist. As a possible further alternative, the colloidal dispersion of the catalyst may be attained by the employment of a suitable organo-metallic compound, such as one of the well-known carbonyl compounds, whereby, at about the temperature of cracking, the catalytic material will be formed in an effective form. As one exemplification of the invention, about 1% or 2% of colloidal alumina may be added to cracking stock such as gas oil, which may then be passed in a single passage through a suitably heated cracking coil which may be heated by convection, by radiation, by immersion in a molten metal bath, or in any other suitable manner. The conversion is effected under pressure, and the resultant cracked products are discharged to an environment of lower pressure in which separation of the formed vapors from the residual liquid and of the spent catalyst can be effected. The amount of catalyst is small, it can be allowed to pass into the residuum without any difficulties being experienced in the further utilization thereof. In case of larger amounts, the residuum may be flushed or distilled to separate it from the catalyst.

For a more complete understanding of my invention, reference will now be had to the drawing in which:

Fig. 1 is a diagrammatic representation of a cracking system constructed in accordance with one embodiment of this invention; and

Fig. 2 is a diagrammatic sectional view of a means for producing a colloidal catalyst for use

in accordance with one embodiment of this invention.

In its preferred embodiment, the invention may be carried out for example in accordance with the diagrammatically illustrated operation shown in Fig. 1 of the drawing. For example, a suitable raw material such as a 32° A. P. I. East Texas light gas oil may be mixed with from 1% to 2% of colloidal alumina in the following manner: The raw material may be drawn from the storage tank 1 and directed through the pipe 2, the valve 3 and the line 4 into the colloidal catalyst mixing tank 5. Preferably, a rather heavy colloidal dispersion—let us say, a 10% dispersion—may be made in this mixing tank, or only 2% may be dispersed, in which latter case the oil containing the therein dispersed catalyst may be drawn through the pipe 6, the valve 7, the pipe 8 and the pump 9, by means of which it may be pumped into the inlet of the coil 10 located in the furnace 11, traversing the entire coil, including the soaking section thereof, designated as 12, issuing from the transfer line 13, and through the pressure reduction valves 14 or 14', whence it is directed into the vapor separator 15, in which separation of vapors and gases from the residuum is effected. The residuum is withdrawn through the valve 16, carrying with it the spent catalyst. Further disposal of the residuum forms no part of the present invention.

Alternatively, a portion of the raw oil may be drawn through the valve 17 and the pipe 8, being pumped by pump 9 into pipe 10 without any catalyst in it, while a portion containing an appropriate amount of catalyst may be drawn through the valve 18 and pumped by the pump 19 through the line 20 and into the soaking section 12 of the coil within the furnace 11, the proportions being so chosen that there will be present in the soaking section the desired amount of catalyst for the cracking of the material passing through the said soaking section of the furnace. The operator thus has complete control of the proportioning of the catalyst and has the choice either of mixing the entire supply of raw material—that is, the gas oil, for example—with the desired amount of catalyst or of producing a more concentrated solution or dispersion of catalyst which is injected into the soaking section 12 of the coil in the furnace 11, while the greater part of the raw material is being pumped into the inlet of the coil 10.

The vapors and gases leaving the vapor separator through the vapor line 21 are discharged into the bubble tower 22. This bubble tower may be under either atmospheric or greater than atmospheric pressure, but in any event separation is therein effected into vapors of the desired end product and gases which are withdrawn from the top of the bubble tower in vapor phase, through the vapor line 23, being then directed into the condenser 24, wherein the condensable portions are liquefied to be sent to suitable collecting instrumentalities which need no further description herein, the gas being conducted to any desired point to be utilized for whatever it may be suitable for.

In the bubble tower a recycle stock of approximately the same specific gravity, or possibly a little lighter, say from 33° to 34° A. P. I., is withdrawn at the bottom through valve 25 and flows through pipe 26 to the recycle pump 27, by means of which it is pumped through the line 28 into the thermal cracking coil 29 located either in furnace 11 or a similar separate furnace. In the coil 29 this recycle stock, without any admixture

of catalyst, is thermally cracked under appropriate conditions, being discharged from the furnace through the transfer line 30 and the pressure reduction valve 31 which leads into the pipe 13, the effluent then being directed from the cracking coil 29 into the same vapor separator 15. It will be noticed that the line 30 is shown as intermediate the valves 14 and 14', this being done in order to give sufficient latitude to the operation. In other words, the effluent from the coil 29 may meet the stream in the line 13 at the same pressure that exists in coils 10 and 12, thus depending upon the pressure reduction valve 14' for the final reduction in pressure before entering the vapor separator, or by suitable adjustments of the valves 14 and 14' any desired changes in pressure may be maintained.

There is also shown diagrammatically a quench line 32 provided with a suitable control valve 33 through which any desired heavier quench oil may be introduced according to methods well understood in the oil conversion art.

It will thus be seen that in accordance with the example shown in the diagrammatic drawing the original raw material may be subjected to a once-through colloidal catalytic cracking procedure, while the recycle stock may be merely thermally cracked. Of course, it is obvious that an entirely separate vapor separation and condensing system may be employed for the cracking of the recycle stock, and such operation is to be construed as within the scope of the present invention.

As examples of the operations of the once-through portion of the process—that is to say, the amount of cracking effected in the colloidal catalytic cracking system—the following results are given, without however limiting the invention thereto:

Experiments on East Texas gas oil treated with colloidal catalyst

Feed stock—32° A. P. I. East Texas light gas oil

Per cent wt. on feed.....				

From the above table it will be seen that a

comparatively low temperature can be employed for cracking, namely, somewhere between 800° and 900°, while obtaining an amount of cracked material in per cent. of volume upon the feed of roughly 30%, having an A. P. I. gravity close to 60° and an octane rating of from 78 to 80, which is an excellent octane rating and makes the product available directly as a motor fuel or as a blending stock. It will be noticed that the characteristics of the cycle oil are also given and that it has an A. P. I. gravity of 34.1°. This cycle stock is that which may subsequently be passed through the thermal cracking system. The overall results, particularly of the combined processes, substantially as herein illustrated, are excellent.

The particular advantage of the present process lies in the fact that it is adaptable to already constructed cracking plants, thereby enabling the use of catalytic cracking without any special constructional details and without necessitating expensive catalyst regeneration, which has hitherto been found necessary in order to make catalytic processes commercially successful. The relatively small amount of catalyst required and the fact that it may with substantial impunity be allowed to remain in the residuum makes the process simple and easy to operate. It will also be noticed that the pressure in the once-through process is comparatively low, being on the order of about 100 pounds per square inch. This is a further advantage because it does not require so strongly constructed an apparatus as is usually necessary in carrying out tube cracking noncatalytically.

Referring now to Fig. 2, the colloidal alumina may be formed directly in the oil by means of an electric discharge between two alumina electrodes. The oil is contained in a vessel 40 having a pair of alumina electrodes 42 and 44 immersed therein. The electrodes 42 and 44 are supported by clamps 46 and 48 secured to a standard 60. Current is supplied to the electrodes by the conductors 52 and 54 which may be connected to any suitable current source. When the current is applied to the electrodes a spark is formed within the body of oil resulting in the liberation of colloidal alumina directly therein.

While the invention has been described in connection with colloidal alumina, it is not to be limited thereto, as obviously other materials capable of colloidal dispersion in the oil may be used; and therefore in the claims covering the combined colloidal and thermal cracking processes, no limitations as to the type of catalyst are intended. Thus, the process might be carried out with colloidal nickel, colloidal carbon, or other well-known cracking catalyst, provided only that the same be colloidally dispersed in part or all of the charging stock, or at least in that part of the charging stock that is directed into the soaking section of the cracking system.

Saving for himself such modifications as lie well within the skill of the oil cracking technologists, the inventor claims:

The process of cracking hydrocarbons which comprises producing an electrical arc between the two aluminum oxide containing electrodes immersed in a body of a liquid hydrocarbon to produce a colloidal dispersion of said oxide in said hydrocarbon, and heating said dispersion to a cracking temperature.

FELIX J. SKOWRONSKI
